UNITED STATES PATENT OFFICE.

THOMAS LEE, OF HOME CITY, OHIO.

DESIGN FOR AN ASH-CAN OR GARBAGE VESSEL.

No. 38,686.

Specification for Design.

Patented July 16, 1907.

Application filed April 12, 1907. Serial No. 367,901. Term of patent 14 years.

To all whom it may concern:

Be it known that I, THOMAS LEE, a citizen of the United States, and residing at Home City, Hamilton county, State of Ohio, have invented a certain new, original, and ornamental Design for an Ash-Can or Garbage Vessel, reference being had to the accompanying drawing, which shows my design in side elevation.

I claim
The ornamental design for an ash-can or garbage-vessel, as shown.

THOMAS LEE.

Witnesses:

C. SPENGEL,
T. LE BEAN.
